GARMENT HANGER

James D. Coney, Detroit, Mich., assignor to
Leonard A. Young, Detroit, Mich.

Application May 20, 1939, Serial No. 274,729

4 Claims. (Cl. 223—88)

This invention relates to improvements in garment hangers.

The main objects of this invention are:

First, to provide a garment hanger of two-piece construction embodying a wire yoke element and a tubular strut element in which the elements are so engaged as to be very effectively retained in assembled relation.

Second, to provide a garment hanger in which, while the parts may be very easily engaged in assembling, they cannot become disengaged even under heavy load.

Objects pertaining to details and economies of the invention will definitely appear from the description to follow. The invention is defined in the claims.

A structure which embodies the features of my invention is clearly illustrated in the accompanying drawing in which:

Fig. 1 is a side elevation of a garment hanger embodying my invention, one arm of the yoke being shown previous to its engagement with the strut by dotted lines.

Fig. 2 is an enlarged end view.

Fig. 3 is an enlarged fragmentary side elevation with the strut in longitudinal section on line 3—3 of Fig. 2.

In the embodiment of my invention illustrated the wire yoke designated generally by the numeral 1 comprises downwardly diverging arms 2, the yoke having a suspending hook 3 at the apex thereof. The strut 4 is a tube of proper dimensions formed as here illustrated by convolutely winding a strip of paper upon itself. This strut has holes 5 in the top thereof which are adjacent to but substantially spaced from the ends of the strut. The arms 2 of the yoke terminate in in-turned fingers 6 having downwardly offset upwardly inclined terminals 7. The ends of the terminals are downwardly curved at 8. These downwardly offset terminals 7 are passed through the holes 5 with the offsets 9 of the fingers engaged in the holes as best shown in Fig. 3.

It will be noted that the ends of the offset terminal portions 7 engage the interior of the strut while portions of the fingers at the outside of the offsets 9 engage the top of the strut. This engagement is with binding or clamping stress when both fingers are engaged with the strut.

When in engaged position the arms of the yoke are spread beyond their normal disengaged position as indicated by dotted lines in Fig. 1 so that the fingers are engaged with the strut not only by the clamping stress applied thereto but the tendency of the arms of the yoke to return to

their normal position also acts to hold the parts in engagement. The clamping engagement of the fingers with the strut is very substantial and they can be disengaged only by springing and distortion of one of the arms of the yoke, that is, the arm that is first disengaged. The reverse is true in assembling.

It will be obvious that the strut may be engaged with the first finger by manipulation of the strut. To engage the second finger it is necessary to distort the parts from their normal position. Owing to the shape of the ends of the fingers they quite easily slip into position, that is, they do not engage or embed themselves in the strut.

I have illustrated and described my improvements in a very practical embodiment thereof. I have not attempted to illustrate or describe other adaptations which I contemplate as I believe the disclosure made will enable the embodiment of my invention as may be desired.

Having thus described my invention what I claim as new and desire to secure by Letters Patent is:

1. A garment hanger comprising a tubular strut having holes in its top adjacent the ends thereof and opening to the bore of the strut, and a wire yoke the arms of which have inturned fingers provided with downwardly offset terminal portions, said offsets being engaged in said holes with their terminal portions within the strut and engaging the top of the inside thereof, portions of the fingers at the outer sides of their offsets being in engagement with the outer surface of the top of the strut.

2. A garment hanger comprising a tubular strut having holes in its top adjacent the ends thereof and opening to the bore of the strut, and a wire yoke the arms of which have inturned fingers provided with downwardly offset upwardly inclined terminal portions having downwardly curved ends, said offsets being engaged in said holes with their terminal portions within the strut and engaging the top of the inside thereof under holding stress, portions of the fingers at the outer sides of their offsets being in engagement with the outer surface of the top of the strut.

3. A garment hanger comprising a tubular strut having holes in its top adjacent the ends thereof and opening to the bore of the strut, and a wire yoke the arms of which have inturned fingers provided with downwardly offset terminal portions, said offsets being engaged in said holes with their terminal portions within and en-

gaging the interior of the strut under holding stress, portions of the fingers at the outer sides of their offsets being in engagement with the top of the strut, the arms of the yoke being spread beyond their normal disengaged position when so engaged with the strut.

4. A garment hanger comprising a strut having holes adjacent the ends thereof, and a wire yoke the arms of which have inturned fingers

provided with downwardly offset upwardly inclined terminal portions having downwardly curved ends, said fingers being engaged in said holes with their terminal portions engaging the strut under stress, portions of the fingers at the outer sides of their offsets being in engagement with the top of the strut.

JAMES D. CONEY.
